By The Firm of Charles H. Wells Attys.

UNITED STATES PATENT OFFICE

149,816

DESIGN FOR A CLOAK RACK OR THE LIKE

Constantine G. Ivelow, La Salle, Ill.

Application May 24, 1946, Serial No. 130,039

Term of patent 14 years

(Cl. D33—8)

To all whom it may concern:

Be it known that I, Constantine G. Ivelow, a citizen of the United States and a resident of the city of La Salle, county of La Salle, and State of Illinois, have invented a new, original, and ornamental Design for a Cloak Rack or the like, of which the following is a specification, reference being had to the accompanying drawing, forming a part thereof.

In the drawing:

The figure is a perspective view of a cloak rack or the like, showing my new design.

I claim:

The ornamental design for a cloak rack or the like, as shown.

CONSTANTINE G. IVELOW.
